UNITED STATES PATENT OFFICE.

BERNT O. BERNTSEN, OF PORT RICHMOND, NEW YORK.

LOCK.

No. 823,987.

Specification of Letters Patent.

Patented June 19, 1906.

Application filed November 17, 1904. Serial No. 233,201.

To all whom it may concern:

Be it known that I, BERNT O. BERNTSEN, a citizen of the United States, residing at Port Richmond, in the county of Richmond and State of New York, have invented new and useful Improvements in Locks, of which the following is a specification.

This invention relates to locks such as are adapted to be applied to children's banks or to safe-deposit boxes and the like.

The objects of the invention are to improve and simplify the construction of such devices; furthermore, to decrease the expense attending their manufacture.

With the foregoing and other minor objects in view, which will appear as the description proceeds, the invention resides in the combination and arrangement of parts and in the details of construction hereinafter described and claimed as a practical embodiment thereof.

In the accompanying drawings, forming part of this specification, Figure 1 is a plan view of a lock constructed in accordance with the invention. Fig. 2 is a similar view showing the cover-plate removed and the lock fitted into the upper end of a suitable box. Fig. 3 is a vertical section on the line 3-3 of Fig. 1, the upper portion of the box to which the lock is applied being shown in section. Fig. 4 is a plan view, partly in section, of a modified lock suitable for use upon a round receptacle. Fig. 5 is a vertical section on the line 5-5 of Fig. 4. Fig. 6 is a similar view on the line 6-6 of Fig. 4. Fig. 7 is a perspective view of a tumbler-disk, spindle, and knob. Fig. 8 is a plan view of the under side of the lock illustrated in Fig. 4. Fig. 9 is a plan view of the movable plate used in connection with the lock illustrated in Fig. 4. Fig. 10 is a similar view of the movable plate used in connection with the lock illustrated in Fig. 1.

Like reference-numerals indicate corresponding parts in the different views.

The improved lock of this invention is adapted to be used in connection with a box or receptacle 1, having inwardly-projecting flanges 2 and 3 at its upper ends. The improved lock itself comprises a bottom plate 4, having upwardly-bent side flanges 5 and 6, which are formed with sockets to receive screws 7 or other suitable fastening devices for securing in position the cover-plate 8. Disposed between the bottom plate 4 and the cover-plate 8 is a movable plate 9, prefer-

ably of the form illustrated in Fig. 10. The movable plate 9 is adapted to slide longitudinally between the side flanges 5 and 6 of the bottom plate in the manner hereinafter described. Formed in the movable plate 9 is a plurality of elongated slots 10, each formed with a projection 11 adjacent to one end thereof. Situated in each of the elongated slots 10 is a tumbler-disk, such as 12, (illustrated in Fig. 7,) each of said tumbler-disks being formed in its periphery with a notch or slot 13. Connected with each of the tumbler-disks 12 and extending upwardly through a suitable perforation in the cover-plate 8 is a spindle 14, with which is connected a suitable knob 15, adapted to be used in turning the tumbler-disk to proper position in opening the box. Connected with the central portion of the movable plate 9 is a spindle 16, which projects upwardly through an elongated slot 17 in the cover-plate 8 and is provided on its upper end with a knob 18. A plurality of teeth or projections 19 is formed upon a downward extension 20 at the forward end of the movable plate 9, as illustrated in Fig. 10 of the drawings. The location of the teeth or projections 19 on the downward extension 20 positions the teeth for engagement with the under side of the flange 2.

Constructed as above described the operation of the improved lock is as follows: When all of the tumbler-disks 12 are turned into such position that the notches 13 are opposite the projections 11, it is possible to slide the movable plate 9 toward the right in Fig. 2 by grasping the knob 18 and forcing it in the proper direction, this movement of the plate 9 being permitted by the entrance of the projections 11 into the notches 13 of the several tumbler-disks. The lock may then be engaged with the flanges 2 and 3 of the box 1 by fitting the bottom and cover plates 4 and 8 over the flange 3, the lock as a whole being prevented from descending into the box by reason of the fact that the cover-plate rests upon the upper edge thereof. When the flange 3 of the box 1 is fitted between the bottom and cover plates, as illustrated in Fig. 3, the lock can be retained in place by forcing the knob 18 toward the left until the teeth or projections 19 engage beneath the flange 2. By then turning the tumbler-disks until the notches therein are out of register with the projections 11 the movable plate is locked securely in advanced position.

The modified form of lock illustrated in Fig. 4 is adapted for application to a round receptacle. The round receptacle, which is designated by 21, is provided at proper intervals with inwardly-projecting teeth or flanges 22 and with inwardly-projecting ribs 23. The bottom plate 24 of the lock is provided with upwardly-projecting segmental flanges 25, having sockets therein to receive screws for holding in position the cover-plate 26. The bottom plate 24 is also formed in its periphery with notches 27, which permit it to pass the inwardly-projecting teeth or flanges 22 when fitting the lock upon the receptacle. Furthermore, the bottom plate 24 is provided in its periphery with suitable notches 28, adapted to straddle the ribs 23 of the receptacle, said ribs and notches serving effectually to prevent any rotation of the bottom plate with respect to the receptacle. The movable plate 29 in this form of the invention preferably is in the form of a Maltese cross having an elongated slot 30 and a projection 31 formed in each of its extremities, as shown clearly in Fig. 9. Located in each of the elongated slots 30 is a tubular disk, such as illustrated in Fig. 7. The rotation of the movable plate 29 is produced by means of a knob 32, which is connected therewith by means of a spindle 33.

The operation of the form of invention illustrated in Fig. 4 is as follows: By turning the tumbler-disks until the notches therein are disposed opposite the projections 31 the movable plate can be rotated until the outer extremities thereof are disposed out of line with the inwardly-extending flanges 22 of the receptacle 21. The lock can then be inserted into the upper end of the receptacle, after which by turning the knob 32 in reverse direction the plate 29 is reversely rotated and the outer extremities are directed beneath the flanges 22, thus locking the receptacle.

From the foregoing description it will be apparent that the lock of this invention is adapted to form a cover for a receptacle. Any suitable arrangement of numbers or symbols may be placed upon each of the knobs 15 of the tumbler-disks and upon the cover-plate in order to produce a permutation-lock.

Changes in the precise embodiment of invention illustrated and described may be made within the scope of the following claims without departing from the spirit of the invention or sacrificing any of its advantages.

Having thus described the invention, what is claimed is—

1. The combination with a receptacle provided with an inturned flange, of a combined lock and cover for the receptacle comprising a cover-plate resting upon the upper edge of the receptacle to support the lock in applied position, a bottom plate smaller than the

cover-plate and provided with upturned flanges to which the cover-plate is secured, a movable plate mounted between the cover and bottom plates, means for operating the movable plate to bring it into engagement with the under side of said flange, and means for locking the movable plate in engagement with the under side of said flange.

2. The combination with a receptacle provided with inturned flanges, of a combined lock and cover therefor comprising a cover-plate adapted to rest upon said flanges, a bottom plate provided with upturned flanges to which the cover-plate is secured, said bottom plate being smaller than the cover-plate and adapted to be brought into engagement with the under surface of one of the flanges of the casing, a movable plate mounted between the cover and bottom plates, means for operating the movable plate to move it into engagement with the under surface of the other flange of said casing, and means for locking the movable plate in engagement with the last-named flange.

3. A lock comprising a casing, having a bottom plate formed with upwardly-projecting side flanges, a sliding plate disposed upon the bottom plate and adapted to be guided in its movement by said flanges, said sliding plate having a plurality of elongated slots therein, each formed with a projection adjacent to one end, a disk located in each of said slots and having a notch in the periphery thereof to receive the adjacent projection, a cover-plate secured upon the flanges of the bottom plate and having a slot therein, a knob having a spindle projecting through the slot in the cover-plate and being fastened to the sliding plate, a plurality of knobs each having a spindle extending through the cover-plate into one of the tumbler-disks, and a downward extension upon the sliding plate, said downward extension lying in the same plane with the bottom plate and being formed with teeth or projections.

4. The combination with a receptacle provided with a flange, of a lock for the receptacle comprising a cover-plate adapted to support the lock in applied position, a bottom plate secured to the cover-plate and spaced therefrom, a movable plate mounted between the cover-plate and bottom plates, means for operating the movable plate to bring it into engagement with the under side of said flange, and means for locking the movable plate in engagement with the under side of said flange.

In testimony whereof I affix my signature in presence of two witnesses.

BERNT O. BERNTSEN.
